UNITED STATES PATENT OFFICE.

WILLIAM G. SIRRINE, OF GREENVILLE, SOUTH CAROLINA.

CLOTHES FRAME.

Application filed October 6, 1922. Serial No. 592,862.

To all whom it may concern:

Be it known that I, WILLIAM G. SIRRINE, a citizen of the United States, residing at Greenville, in the county of Greenville and State of South Carolina, have invented certain new and useful Improvements in Clothes Frames, of which the following is a specification.

The present invention relates to improvements in clothes frames in which provision is made for holding and protecting clothing which has been recently pressed and which is to be transported in a box from the tailor to the customer.

15 An object of the invention is to provide a collapsible frame adapted to fit within the box to hold the box in a distended condition at all times and to prevent its collapse locally which at the present time results in 20 the mussed condition of the clothing before it arrives at its destination.

Another object of the invention is to provide such a frame which also receives a hanger upon which the clothing is suspended so as to take off the container all of 25 the strain of supporting the clothing, the frame being so arranged in conjunction with the hanger as to freely suspend the articles of clothing from the same point from which 30 the container is being carried, so that the clothing may not creep into one end of the box and the shape is thus preserved.

A further object of the invention resides in providing an improved frame of a light 35 skeleton character which will not add appreciably to the weight to be carried, which is inexpensive in construction, and which admits of collapse to enable the frames to be shipped in quantities within a relatively 40 small space.

A further object is to provide a frame connected to another frame and separated by means of light irons or braces at the four corners for the purpose of providing 45 a luggage carrier so as to receive two or more hangers upon which to suspend coats, vests and other garments and to provide a cross-bar upon which to suspend two or more pairs of trousers or other garments. 50 The immediate object of this device being to place the frame with its clothing thus suspended within a light traveling case which is to be carried in such way that the garments depend from the hangers and the cross-bar above mentioned and are transported without being gotten out of shape.

With the foregoing and other objects in view, the invention will be more fully described hereinafter, and will be more particularly pointed out in the claims appended 60 hereto.

In the drawings, wherein like symbols refer to like or corresponding parts throughout the several views,

Figure 1 is a perspective view of the improved frame constructed according to the present invention.

Figure 2 is a similar view showing the frame collapsed.

Figure 3 is a front view of the frame with 70 articles of clothing indicated in dotted lines as suspended therefrom.

Figure 4 is an edge view showing in dotted lines the container and clothing.

Figure 5 is a perspective view of a double 75 frame arrangement comprising two frames, spaced apart, but connected together, each frame being constructed according to the present invention.

Figure 6 is a similar view showing the 80 frame with a hanger attached and from the hanger a coat suspended, the skirts of the coat being folded back from about the waist line.

Figure 7 is a side view of the frame with 85 the clothing removed therefrom.

Figure 8 is an edge view showing in dotted lines the container and the clothing in place; and

Figure 9 is a detail view of an auxiliary 90 supporting slat that may be used with the double frame arrangement of Figs. 5 to 8.

Referring more particularly to Figs. 1 to 4 of the drawings, 1 and 2 designates side standards or uprights of the frame which 95 are preferably made of light thin lath which is of a flat construction and possessed of the necessary strength and rigidity to support the articles of clothing when combined with a bottom rail 3, a top rail 4 and 100 an intermediate bracing rail 5, all of which extend transversely or at substantially right angles to the standards 1 and 2 and which are affixed thereto preferably at one point shown, as for instance, by the screw 6. 105 Cross rails 5^a are also provided towards the lower end of the frame.

The top rail 4 carries a hook 7 connected thereto, as by a screw 8 or other fastening. This hook hangs below the rail so as to receive the clothes hanger 9, indicated in dotted lines in Fig. 3, and upon which the coat

10 and trousers 11 are shown to be suspended.

The frame is also strengthened by the diagonal braces 12 extending across each of 5 the upper corners of the frame and connecting the uprights 1 and 2 and the top rail 4.

In Figure 4 I have illustrated (in dotted lines) a box or container composed of the telescoping body 14 and cover 15 having 10 the handle 16 by which to transport it.

The frame having the clothing suspended thereon as indicated in Figure 3 is placed as a unit in the box 14 and the cover 15 is placed thereon and secured in any suitable 15 manner.

It will be seen that the handle 16 extends directly above the hook 7 from which the clothing is supported and that therefore the articles of clothing are held in the loose 20 suspended condition and will not be apt to slide down toward the lowermost portion of the box which destroys the crease. When the clothing is delivered to the customer the box may be simply set up and left in 25 this condition until the use of the clothing is required. During all of this time the clothing will be preserved in substantially the same condition in which it was received from the tailor's iron, and additionally the 30 container forms a protection against dust, moths and the like.

It will be noted that the intermediate brace rail 5 occupies a position near the top of the frame but spaced suitably below the 35 top rail 4; and this intermediate rail 5 is placed where it will encounter the upper portion of the clothing at approximately the hanger 9 and it will interpose an obstacle to the swinging of the clothing laterally through the frame such as would occur if this brace were not present. The brace constitutes a barrier to the too-free movement of the clothing about in the container, as this movement tends to disarrange the clothing upon the hanger and to 40 allow it to strike against the sides of the container. Moreover the brace 5 being at the upper position near the top rail 4 braces the frame near the point of support of the 45 clothing, and it forms with adjacent parts a rectangular top frame which is rigid, secure, and which avoids edgewise vibration of the collapsible frame. Moreover, the diagonal braces further assist to prevent 50 this edgewise vibration of the standards 1 and 2 and serve to reinforce the standards against being bent in flatwise direction incident to the weight of the clothing. The 55 fastenings employed at each of the points 60 6 are desirable as they need only be loosened slightly to permit the frame to be collapsed and due to the arrangement of bracing, such single fastening may be employed without any untoward result in the 65 rigidity and usefulness of the frame.

The intermediate brace rails 5^a occupy a position near the bottom of the frame and are spaced suitably to offer a support for the garment, and with the brace rail 5 provide a suitable carrier for the garment 70 when the frame is lifted. These intermediate rails also act as braces for the frame. By the use of these supporting cross rails the frame may be placed upon a table, bed or other support, and the garments conveniently place on the hanger on the cross bar so that the whole frame may be then lifted and placed within the container or the box. 75

Where the container is of light material, the handle being directly over the frame 80 may be secured to the frame by means of strings, straps or wires passing through perforations in the container so that the handle is firmly fixed to the frame itself 85 and no weight is placed upon a container.

When folding a frame as indicated in Figure 2, one of the fastenings of the diagonal braces 12 and one of the fastenings of the other brace 5 are preferably removed wholly in order that these braces may be collapsed against adjacent portions of the frame. In this condition they will not interfere with the movement of the standards 1 and 2 together in an edgewise direction or approximately together, this being effected 90 of course only after loosening the screw. In the collapsed condition the device may be shipped in a smaller space incurring only 95 small transportation charges.

Figure 5 is designed to show a double arrangement, one frame being attached to another to form a rectangular boxlike construction, one frame only being provided with the intermediate cross rails. The two frames are separated by short braces of steel 100 or other material. Each of the frames carries a hook to support a hanger. There is provided a cross bar of wood from which to suspend trousers or other garments. This cross bar receives its support at each end 105 from two of the separating brackets. Preferably the one frame is separated from the other by about four and one-half inches so as to provide room for two suits of clothes 110 without crushing. Each hanger may carry 115 a coat and vest or other garments, and the supporting bar which rests between them may carry the trousers or other garments.

Figure 6 shows one frame side by side with another, with a coat hanging from the 120 frame which carries the intermediate cross braces. It will be seen that the shoulder of the coat bears against the cross brace 5 while the waist and skirt of the coat rest upon the 125 cross rails 5^a.

Diagonal end braces 17 may be provided to stiffen the structure.

Figure 8 shows the double frame arrangement with a coat depending from each hanger, and the trousers supported by the cross 130

bar between the coats. The carrying handle of the container or box is also shown above. This frame, intended for passengers' luggage, does not require that the frame be suspended by strings, straps or wires to the handle, the traveling box or bag being strong enough to carry the weight because it is distributed by means of the frame.

Figure 9 shows the bar 18 intended to 10 carry the trousers or other garments supported by the brackets. Under the bar is shown a block 19 at each end to prevent the bar from slipping.

It will be appreciated from the foregoing 15 that I have provided a simple and effective frame for carrying clothing in which the latter may be preserved intact during the period of transportation.

It is obvious that various changes and 20 modifications may be made in the details of construction and design of the above specifically described embodiment of this invention without departing from the spirit thereof, such changes and modifications being restricted only by the scope of the following 25 claims.

Having thus described my invention what I claim and desire to secure by Letters Patent of the United States is:—

30 1. A frame for supporting clothing comprising relatively light thin standards, upper and lower rails collapsibly connecting the standards, and means carried by the upper rail for supporting a garment hanger, substantially as described.

2. A frame for supporting clothing comprising relatively light thin standards, upper and lower rails collapsibly connecting the standards, and means carried by the upper rail for supporting a garment hanger, substantially as described.

3. A collapsible frame for carrying clothing comprising relatively thin light standards, rails connecting the upper and lower ends of said standards, means carried by the upper rail for receiving a garment hanger, and an intermediate rail connected between said rails near their upper ends and spaced from said top rail, substantially as 45 described.

4. A collapsible frame for carrying clothing comprising relatively thin light standards, rails connecting the upper and lower ends of said standards, means carried by the upper rail for receiving a garment hanger, and an intermediate rail connected between said rails near their upper ends and spaced from said top rail, with lower parallel cross rails near the base rail, substantially as 55 described.

5. A garment carrying arrangement comprising two oppositely disposed rectangular frames, each frame being provided with means for suspending a garment hanger 65 therefrom, and one of said frames being provided with transverse slats, and braces connecting said frames together but holding the same in the parallel relation, substantially as described.

6. A garment carrying arrangement comprising two oppositely disposed rectangular frames, each frame being provided with means for suspending a garment hanger therefrom, and one of said frames being provided with transverse slats, and braces connecting said frames together but holding the same in the parallel relation, with a removable slat provided with downwardly projecting stop lugs mounted between the upper 75 portions of said parallel frames, substantially as described.

WILLIAM G. SIRRINE.
